UNITED STATES PATENT OFFICE.

NATHANIEL S. REEDER, OF NEW YORK, N. Y., ASSIGNOR TO PRESSED STEEL CAR COMPANY, OF PITTSBURGH, PENNSYLVANIA, A CORPORATION OF NEW JERSEY.

CAR-ROOF CONSTRUCTION.

1,328,200.

Specification of Letters Patent. Patented Jan. 13, 1920.

Application filed December 19, 1916. Serial No. 137,770.

To all whom it may concern:

Be it known that I, NATHANIEL S. REEDER, a citizen of the United States, residing in New York city, in the county of New York and State of New York, have invented certain new and useful Improvements in Car-Roof Constructions, of which the following is a specification.

This invention relates to a new and useful improvement in car roof construction, an object being to provide a roof combining a maximum of strength and rigidity with a minimum of weight, and which will be simple in construction and capable of being manufactured cheaply.

Another object of the invention is to provide an improved carline which can be manufactured by pressing a rectangular shaped plate into the desired shape, thus obviating the use of expensive blanking dies or the production of scrap metal, such as is usual when such articles are formed from irregularly shaped plates.

Another object of the invention is to provide a roof construction embodying simple and effective means for the attachment and adjustment of the roof sheets to the carline, and also having a weather-proofing member which engages the edge portions of the roof sheets.

Another object of the invention is to provide simple means for attachment of the roof sheets and weather-proofing member to the carline which will permit of the easy removal and replacement of such sheets or member.

Another object of the invention is to provide a carline to which the roof sheets may be secured in such a manner as to provide weather-proof expansion joints between the roof sheets of the car.

A further object of the invention is to provide a carline which is adapted to conduct to the exterior of the car any water which may leak through the joints between the roof sheets.

Referring now to the drawings in which like reference characters refer to like parts, Figure 1 is a fragmental plan view of a portion of a car roof and carline constructed in accordance with the invention; Fig. 2 is a sectional view of the same taken on line 2-2 of Fig. 1, the roof sheets and weather-proofing member being extended farther

than shown in Fig. 1. Fig. 3 is a detail sectional view taken on line 3-3 of Fig. 1, and Fig. 4 is an end elevation of the carline with the roof sheets and weather-proofing member removed, and Fig. 5 is an enlarged detail sectional view of a modification of the roof construction.

Referring now in detail to the drawings, 1 indicates the side plates of the car which may be of any suitable form or construction, but as shown in the drawings are preferably of Z section. 2 indicates the carlines, each of which is made from a rectangular metal plate preferably bent to form a member of channel or U section having lateral flanges 3, 3 extending outwardly therefrom in opposite directions. This channel shaped member has its deepest portion at substantially its center, and tapers to its shallowest portion at each end, whereas the lateral flanges 3, 3 are widest at the ends of the carline, and taper toward its center portion where the flanges are narrowest. From an inspection of Figs. 1 and 2 of the drawings, it will be seen that the width of the flanges 3, 3 varies in proportion inversely to the depth of the channel portion of the carline, and it follows that the carline may be pressed from a plate of rectangular shape having a uniform width throughout its length, thus making unnecessary the use of expensive blanking dies, and obviating the production of scrap metal, as hereinbefore referred to. The end portions of the flanges 3, 3 are slit, as at 4, 4 for some distance back from the ends of the carline, and the outer portions 5, 5 of the flanges are bent downwardly, as shown in Figs. 2 and 4, until the end portions 6, 6 of such flanges are in the same horizontal plane as the lower surface of the end of the channel shaped portion of the carline. The ends of the channel shaped portion of the carline may be secured to the side plate by means of rivets 7 or other suitable means, and the downwardly bent portions 5, 5 of the lateral flanges 3, 3 may also be secured to the side plate by similar means 8, 8.

The roof sheets 9, 9 preferably extend continuously across the width of the car and at their outer edges are provided with down-turned flanges or portions 10, which contact with the vertical portion 11 of the side plate. It will readily be seen by those skilled in

the art to which this invention appertains that if a car is desired of the ventilated type, the flanges 10 of the roof sheets may be extended outwardly beyond the vertical portion 11 of the side plate 1 in order to provide a space 23 between the flange of the roof sheet and the side plate, through which air may freely pass in and out of the car, thus permitting efficient ventilation of the car. The edge portions 12 of the roof sheets 9 are turned downwardly and are adapted to extend within the channel portion of the carline 2, when such plates 9 are in their proper position on the carlines, each of the carlines being provided with a plurality of members 13, 13, 13 which are secured within and across the channel portion thereof. The members 13 may be of Z, channel or other suitable shape, and are each provided with flanges 14, which extend longitudinally of the carline, and which may be secured to the webs of the channel portion thereof, as shown in the drawings, by any suitable means. The intermediate portion 15 of these members is provided with a perforation 16 into which the hooked end 17 of a bolt 18 may be inserted for the purpose of securing the roof sheets and weather-proofing element to the carline.

19 indicates a weather-proofing member which preferably is formed of a metal plate bent to form a shallow channel section having flanges 20, 20 extending outwardly and slightly downwardly therefrom in opposite directions. This member 19 extends for preferably the full width of the car, and is provided at intervals with perforations through which the threaded ends of the bolts 18 mounted in the members 13 are adapted to pass. The ends of the bolts 18 are provided with nuts 21 which when tightened are adapted to engage the member 19 and force the flanges 20, 20 thereof into close contact with the roof sheets 9, 9, thus forming a water-tight joint between the roof sheets. The members 19 are preferably made resilient so that should the nuts 21 become accidentally loosened, the channel portions of these elements will move upward automatically with the nuts, and while in contact with such nuts will hold the flanges 20, 20 in close contact with the roof sheets 9, 9. It will be seen from the foregoing description that the roof sheets 9, 9 are slidably clamped or held between the flanges 20, 20 of the elements 19, and the flanges of the carline 2, thus allowing the roof plates to move relative to each other and to the carline when the car has become deformed due to railway service conditions. This construction also permits of the expansion and contraction of the roof plates due to changes in temperature or weather conditions. Should any water leak through the joints formed by the roof sheets 9 and the

flanges 20 of the member 19, as above described, due to damage of the member 19 or from other causes, it will drop within the channel portion of the carline 2, and as a result of the downward and outward inclination of the web portion of such channel from the longitudinal centerline of the car to the side of the car the water will be conducted to the exterior of the car, a slight space being provided between the roof sheet 75 and the side plate at the end of the channel portion of the carline, as shown at 22 in Fig. 2.

Although in the drawings and foregoing description only portion of one carline and 80 the roof plates and the several parts coöperating therewith are illustrated and described, it will be understood by those skilled in the art that both ends of the carline are substantially alike, and that a railway car 85 roof is composed of a plurality of such parts.

From the foregoing description, it will be seen that many minor changes in the details and arrangement of parts may be made without departing from the spirit and scope 90 of the invention as defined by the appended claims.

Having thus described the invention, what I claim as new and desire to secure by Letters Patent is:

1. A roof carline having a laterally extending flange, said flange being bifurcated, and one of the resultant portions bent downwardly.
2. A roof carline having a laterally extending flange, the end portions of said flange being bifurcated, and one of the resultant portions bent downwardly.
3. A roof carline having a central portion, and an integral laterally extending bifurcated flange, and one of the resultant portions bent downwardly.
4. A roof carline having a body portion and a laterally extending flange, the end portions of said flange being bifurcated, and one of the resultant portions bent downwardly.
5. A roof carline having a body portion of substantially U shape and a laterally extending flange, the end portions of said flange being bifurcated.
6. A roof carline having laterally extending flanges, the end portions of each of said flanges being bifurcated.
7. A roof carline having a central portion, a laterally extending flange on each side thereof, the end portions of said flanges being bifurcated.
8. A roof carline having a central portion of substantially U shape and a laterally extending flange on each side of said central portion, the end portions of said flanges being bifurcated.
9. A roof carline having a central portion of substantially U shape, deepest at its cen- 130

ter and tapering toward its ends, a flange extending laterally from each side thereof, said flanges being widest at their ends and tapering toward their centers, the end portions of said flanges being bifurcated.

10. A roof carline having a body portion, a flange extending laterally therefrom, the end portion of said flange being bifurcated, one of the resultant portions being bent downwardly from its original plane into the same horizontal plane as the lower portion of the body.

11. The combination, with the side plate of a car, of a carline secured thereto, said 15 carline having a laterally extending flange, the end portions of said flange being slit, and a portion of the flange bent downwardly and secured to said side plate.

12. The combination, with the side plate of a car, of a carline secured thereto, said 20 carline having laterally extending flanges, the end portions of said flanges being split, and portions of the flanges bent downwardly and secured to said side plate, and roof sheets resting upon said flanges and out of 25 contact with the downwardly bent portions of said flanges, said roof sheets having downwardly depending end flanges spaced away from the end of said carline and web of said side plate.

In testimony whereof I affix my signature in the presence of two witnesses.

NATHANIEL S. REEDER.
